UNITED STATES PATENT OFFICE.

HARRY C. BREWSTER, OF SHREVEPORT, LOUISIANA.

DRILLING MACHINE.

Application filed February 15, 1926. Serial No. 88,476.

This invention relates in general to safety devices for use in hydraulic drilling machines, and more particularly relates to a safety slip ring arrangement especially designed for use with the rotaries employed in rotary drilling for the purpose of preventing any object from falling into the well while drilling or when removing the pipe from the well.

In carrying out the present invention, the stationary bed of the rotary is provided with a slip ring which receives a safety ring having an opening through which the drill stem loosely extends. The stationary slip ring of the bed is in addition to the movable slip ring, carried by the rotary. With this arrangement, when drilling or when removing the drill pipe any objects that might fall or be dropped will be caught by the safety ring. The safety ring permits the couplings on the drill stem to pass therethrough but when the drill bit engages the safety ring the safety ring is lifted out of the stationary slip ring and up through the movable slip ring mounted on the rotary.

Other objects and advantages reside in certain novel features of the construction, arrangement and combination of parts which will be hereinafter more fully described and particularly pointed out in the appended claims, reference being had to the accompanying drawing forming a part of this specification, and in which:

Figure 1 is a view partly in section and partly in elevation showing the present invention embodied in a rotary,

Figure 2 is a perspective view of the stationary slip ring, and

Figure 3 is a perspective view of the safety ring.

Referring to the drawings the numeral 1 designates generally a rotary which may be of any standard or conventional type, and which has a stationary bed 2 on which the rotating frame 3 is mounted. The rotating frame or part 3 carries a slip ring 4 in accordance with the usual practice.

The present invention proposes the provision of a bottom slip ring arrangement which includes a stationary slip ring 5 secured to the stationary bed 2 of the rotary in any suitable manner and having an inner

removable stationary ring 6. The inner face of the outer ring 5 is inclined as indicated at 7 and the outer periphery of the inner ring 6 is similarly inclined, so that when the inner ring 6 is dropped into the outer ring 5, it will be engaged therewith and supported thereby, as shown in Figure 1. The inner ring 6 has an inwardly directed annular flange 8 around its lower edge which provides a supporting shelf for an annular safety ring 9. The safety ring 9 is flat and has its outer periphery resting on the shelf provided by the flange 8. Centrally this ring 9 has an opening 10 designed to loosely receive the drill stem S and its coupling. With this arrangement, should an object be dropped or fall down through the ring 4, it will be supported by the safety ring 9 during the drilling operation as well as when removing the drill stem. When the drill bit engages under the safety ring 9 it lifts the safety ring 9 up through the rotary. These advantages are had and no interference is presented to the normal drilling operation which is carried out in accordance with the conventional practice.

I claim:

1. A rotary having the usual slip ring mounted on the rotating part thereof and also having a bed provided with a slip ring arrangement including an outer ring fixed to the bed and an inner ring carried within the outer ring and provided with an in-turned annular flange presenting a shelf, and a safety ring mounted on said shelf and having an opening through which the drill stem and its couplings loosely pass, the safety ring being designed to prevent objects from falling or dropping down into the well when drilling or when removing the drill stem.

2. A rotary having the usual slip ring mounted on the rotating part thereof and also having a stationary bed, an in-turned shelf supported on the stationary bed and a safety ring mounted on said shelf and having an opening through which the drill stem and its couplings loosely pass, the safety ring being designed to prevent obstructions from falling or dropping into the well when drilling or when removing the drill stem.

HARRY C. BREWSTER.
